UNITED STATES PATENT OFFICE.

JOSEPH SCHOEPE, OF NEW YORK, N. Y.

METHOD OF MAKING A TOOTH-BRUSH.

1,118,156.

Specification of Letters Patent.

Patented Nov. 24, 1914.

Application filed January 13, 1914. Serial No. 811,798.

To all whom it may concern:

Be it known that I, JOSEPH SCHOEPE, a subject of the German Emperor, and residing at 414 East One Hundred and Sixty-6 third street, New York city, county of Bronx, State of New York, have invented a certain new and Improved Method of Making a Tooth-Brush, of which the following is a specification.

10 This invention relates to a method of making a tooth brush which is so constructed that the bristles will straddle the teeth so that the latter will become thoroughly cleaned at their grinding surfaces as well as 15 at their outer and inner sides. The brush is so organized, that its component parts may be readily formed and that they may be assembled in a reliable and simple manner.

In the accompanying drawing: Figure 1 20 is a front view of the brush back before being bent; Fig. 2 a similar view of the stock; Fig. 3 an end view of Fig. 1; Fig. 4 a similar view of Fig. 2; Fig. 5 a front view of the brush back and stock showing them 25 assembled, but prior to bending; Fig. 6 an end view of the brush complete, and Fig. 7 a front view of the brush complete, with the handle portion partly broken away.

The brush comprises essentially a head 10 30 which is made of U shape and from which extends a preferably integral handle 11, the whole constituting the stock. Head 10, is somewhat thinner than handle 11, and is provided on its inner concave face with a 35 pair of parallel undercut flanges 12, that extend at right angles to handle 11. These flanges engage the beveled longitudinal edges 13 of the brush back 14, which is also of U shape and has a curvature corresponding to that of head 10. The brush back is 40 provided with two opposed rows of bristles

15, which project from both sides as well as from the crown thereof so as to form between their working edges a substantially triangular opening 16 adapted to straddle a 45 tooth. It will be seen that by manipulating the brush in the ordinary manner, the bristles will brush the front, the back and also the grinding edges of the teeth so that the latter are thoroughly cleaned.

50 In constructing the brush, aluminium or other bendable material should be used for the head 10 as well as for the back 14. The head is first perfectly straight forming a cross bar to the handle, the whole being substantially T shaped (Fig. 2). The back 14 55 which is also formed of a straight strip (Fig. 1) is slipped lengthwise into the head, so that the flanges 12 of the latter engage the beveled edges 13, and thus securely affix 60 the back to the head (Fig. 5). The head together with the back are then bent into the curved form desired (Fig. 6) by which operation the back becomes permanently 65 locked to the head against longitudinal withdrawal thereby forming the U-shaped composite brush head.

I claim:

Method of making a tooth brush which consists in forming a bendable T shaped 70 stock having a flanged head, slipping a bendable bristle-carrying back into engagement with said head, and simultaneously bending the head and back whereby the back becomes permanently locked to the 75 head to form a composite U-shaped brush head.

JOSEPH SCHOEPE.
